(57) **CLAIM**

The ornamental design for an electric mop, as shown and described.

DESCRIPTION

FIG. 1 is a top-front perspective view of an electric mop according to the present invention;

FIG. 2 is a bottom-rear perspective view thereof;

FIG. 3 is a front elevation view thereof;

FIG. 4 is a rear elevation view thereof;

FIG. 5 is a left side view thereof, the right side view being a mirror image thereof;

FIG. 6 is an enlarged top plan view thereof;

FIG. 7 is an enlarged bottom plan view thereof;

FIG. 8 is an enlarged top-front perspective view of a feature shown within the area designated as 8 in FIG. 1;

FIG. 9 is an enlarged top-front perspective view of a feature shown within the area designated as 9 in FIG. 1;

FIG. 10 is an enlarged bottom-rear perspective view of a feature shown within the area designated as 10 in FIG. 2;

FIG. 11 is an enlarged bottom-rear perspective view of a feature shown within the area designated as 11 in FIG. 2;

FIG. 12 is an enlarged front elevation view of a feature shown within the area designated as 12 in FIG. 3;

FIG. 13 is an enlarged rear elevation view of a feature shown within the area designated as 13 in FIG. 4;

FIG. 14 is an enlarged left side view of a feature shown within the area designated as 14 in FIG. 5;

FIG. 15 is an enlarged left side view of a feature shown within the area designated as 15 in FIG. 5;

FIG. 16 is an enlarged left side view of a feature shown within the area designated as 16 in FIG. 5;

FIG. 17 is an enlarged bottom plan view of a feature shown within the area designated as 17 in FIG. 7;

FIG. 18 is a cross-sectional view taken along lines 18-18 in FIG. 3; and,

FIG. 19 is an enlarged fragmentary cross-sectional view of a feature shown within the area designated as 19 in FIG. 18. The broken lines shown in the drawings are for the purpose of illustrating the portions of the electric mop and form no
